 tion of Delaware

Application December 30, 1950, Serial No. 203,644

9 Claims. (Cl. 74—483)

1

Our present invention relates to switch mechanisms and more particularly to multiple push-button switches.

There frequently arises a situation in which it has been found desirable to provide push-button means for switching electrical circuits either singly or in groups. An example of such a situation is an interoffice communication system wherein it is frequently desirable to call a single party or to call several parties simultaneously as in a conference call. In addition, it is frequently important that such switching means be capable of withstanding considerable mechanical shock without interrupting the circuits that may be completed through the switch mechanism.

In conventional push-button switches there is provided an interlocking means whereby the depression of one push-button plunger releases a previously depressed plunger. In such switches, more than one plunger may be locked in the depressed position only by simultaneously depressing the selected plurality of plungers or by manually holding the previously depressed plungers down while depressing additional selected plungers.

Further in conventional push-button switches, the plungers are held depressed by a single latch member. Although the latch member may be spring biased, a sudden jolt or jar may cause the single latch member to release the depressed plunger. Such a feature would be disadvantageous and, particularly when the switch is employed in mobile equipment, may frequently interrupt operation.

Accordingly, it is an object of our present invention to provide an improved push-button switch mechanism which obviates the above objectionable features.

It is another object of our present invention to provide an improved push-button switch mechanism which is characterized by shockproof latching of the switch plungers.

A further object of our present invention is the provision of an improved push-button switch as set forth in which means are provided for cumulatively latching a plurality of switching plungers.

It is still another object of our present invention to provide a switch as set forth which may be released from a remote point.

In accomplishing these and other objects we have provided a push-button switch having a plurality of contact operating plungers of substantially identical construction. A double acting latching means provides shockproof locking of

2

the actuated sections. Individual, independent latching segments permit cumulative locking of the several switch plungers, all of which may be released by the operation of a single release button.

A better understanding of our present invention may be had from the following detailed description when read in connection with the accompanying drawings in which:

10 Figure 1 is a side view of a portion of a switch constructed in accordance with the present invention and showing four push-button plungers, one of which may be a release plunger,

Figure 2 is a top view, partly broken away, of 15 a portion of a switch constructed in accordance with the present invention and showing five plungers,

Figure 3 is an enlarged view similar to Figure 2 but showing only the details of the center 20 plunger,

Figure 4 is an end view, partly in cross section, taken along the line 4—4 of Figure 1 and looking in the direction of the appended arrows,

Figure 5 is a view similar to Figure 4 but showing the plunger in a depressed position, and

Figure 6 is a top view, partly in section, taken along the line 6—6 of Figure 1 illustrating a different form of the present invention.

Referring more particularly to the drawing, 30 there is shown in Figure 1 a portion of a switch mechanism made in accordance with the present invention wherein a plurality of push-button plungers 2a, 2b, 2c, 2d are supported in a framework consisting of a lower frame member 4, a cover member 6 and a pair of end supports 8 (one shown). The first plunger 2a is a release plunger (discussed in greater detail hereinafter). The remainder of the plungers 2b, 2c, 2d, etc. are contact operating plungers. A set of spring pile-up contacts 10, one set for each of the operating plungers, is actuated by a contact operating cam 12 on the respective operating plungers 2b, 2c, etc.

These contact operating cams 12 are preferably made of an insulating material. Each of the plungers are normally biased into an upward or non-operating position by a spring 13. Below the cover member 6, there is a channel member 14 with an opening 16 therethrough for each of the plungers. Nested in the channel member is 45 a pair of latch members 18 and 20 (see Fig. 6). These latch members lie in a common plane side-by-side and have a series of complementary apertures therein, one for each of the plungers. The complementary apertures are preferably in the 50 form of semi-circular notches 22, 24 cut into the

edge of each of the latch members 18, 20. The notches 22 in one of the latch members 18 face the notches 24 in the other of the latch members 20. The notches in one of the latch members are adapted to be aligned with the corresponding notches of the other member, however, they are normally spring biased into misalignment. We have also provided a retaining plate 25 which fits the upturned edges of the channel member 14 and serves to retain the latch members 18 and 20 in channel without binding. On each of the plungers there is a frusto-conical latch operating cam 26 which, upon depressing one of the plungers, displaces the latch against the spring bias to align the complementary apertures. If the plunger is further depressed until the base of the cone 26 (i. e. the largest diameter) is below the latch members, the spring bias causes the latch members to close over the cam, locking the plunger in its depressed position. In such depressed position, the contact operating cam actuates the spring pile-up contacts 10 as shown in Figure 5. When, as shown in Figure 6, the latch members or plates 18 and 20 are common to all of the plungers, the plungers are interlocked. That is, the depressing of a second plunger will cause a previously locked plunger to be released.

It should be noted at this point that when the plungers are locked in the depressed or operating position, the respective latch members 18 and 20 lock over the base of the cam 26 from opposite directions. With the spring bias on one latch plate 18 exerting its influence in one direction and the spring bias on the other latch plate 20 exerting its influence in the opposite direction, the two latch plates lock over the cam 26 substantially as shown on the second plunger 2b of Figure 2. Thus, while a shock or jolt on either one end of the switch mechanism may cause one of the latch plates to move into an alignment with respect to the base of the cam 26, the other latch plate is not so displaced. Therefore, the depressed plungers are not released by a severe jolt or shock to the mechanism from either end.

In some circumstances it may be desirable to be able to clear all lines from a remote position such as central control desk. Such a clearing of the line may be effected by the inclusion of a solenoid or other electro-mechanical means 28 (Fig. 6) the armature of which is mechanically coupled to the latch plates 18 and 20 and which, when excited, moves the latch plates 18 and 20 to a position where the complementary apertures are in alignment, releasing any plunger that may have been depressed. Thus, an executive may interrupt existing circuits to permit the issuance of important and urgent orders or instructions without the necessity of waiting until the line is free.

In Figures 2 and 3 there is illustrated a modified form of our invention which provides means for cumulatively locking down a plurality of contact operating plungers 2b, 2c, etc. One of the common latch plates 18 has been replaced by a plurality of separate, independently operable latch segments 30b, 30c, 30d, etc., each with its own bias spring 32. In the arrangement shown in Figures 2 and 3 these bias springs 32 are anchored in the common latch plate 20 in the manner of a cantilever, the free end thereof pressing against one end of the latch segments 30b, 30c, 30d. Thus the counteraction of the springs also provides a biasing force for the common latch plate 20 in a direction opposite to that applied to the latch segments. If any of the contact

operating plungers 2b, 2c, etc. are depressed to their operating position, the common latch plate 20 is moved to a position where all of the notches 24 are in alignment with the latch operating cams 26 on the respective plungers. However, only the latch segment associated with the particular plunger that was depressed moves to a position to clear the latch operating cam. Thus, if any contact operating plunger has been previously depressed, the subsequent pressing of another contact operating plunger will not cause the previously locked plunger to be released. Several plungers may be conveniently depressed, sequentially, without the necessity of holding down previously locked plungers while depressing the subsequent ones as usually required on mechanisms having interlocked keys such as shown in Figure 6.

Since the depressing of subsequent plungers does not release previously locked plungers, means are provided for releasing the locked plungers. For this purpose we have provided a release plunger 2a which, so far as the plunger itself is concerned, may be substantially identical with the contact operating plungers. Associated with the release plunger is a latch segment 30a which is similar to the other latch segments but differs from them in that instead of being free to slide in the channel member 14, it is secured thereto, for example, by a pair of screws 34. Each of the latch segments 30b, 30c, etc. associated with one of the contact operating plungers has a pin 36 which extends through a slot 38 in the upturned wall of the channel member 14 adjacent to each of the contact operating plungers. These slots 38 are so positioned with respect to the pins 36 as to limit the movement of the latch segments 30b, 30c, etc. in the direction of the bias supplied by springs 32, but permit sufficient freedom of movement of the segments in the opposite direction to allow the notches in the segments to be aligned with and by the latch operating cams on the plungers. The channel member 14 is not rigidly secured in the structure, but rather has a limited freedom to move longitudinally. Therefore, when the release plunger 2a is depressed, the latch operating cams thereon move the common latch plate 20 to the left, as viewed in Figures 2 and 3, to a position where the notches therein are in alignment with all of the respective plungers. Simultaneously therewith, the cam on the release plunger also moves the segment 30a, and hence the channel member 14, to the right. When the channel member 14 is moved to the right, the latch segments 30b, 30c, 30d, etc. must also move to the right since the pins 36 are butting against the left end of the respective slots 38. It should now be apparent that when the release plunger is depressed any contact operating plunger that has been locked down would be released.

The openings 16 (shown in dotted lines in Figures 2 and 3), in the channel member 14 associated with each of the contact operating plungers need be only large enough to pass the largest diameter of the latch operating cam. They are made oval in shape to prevent interference with the latch operating cams 26 when the release button is pressed and the channel member 14 moves to the right as viewed in the drawings. However, the opening associated with the release plunger 2a should be aligned and coextensive with the notch in the latch segment 30a. With this arrangement, the release plunger may be locked in its depressed position, but it is held down only by

the common latch plate 20, the channel member 14 (and, hence, all of the latch segments) being held in the right hand position by the channel member bearing on the latch operating cam of the release plunger. Since the common latch plate is moved to the left when any of the plungers are operated, the release plunger will be released upon depressing one of the contact operating plungers.

While the release plunger has been distinguished from the contact operating plungers in nomenclature, this has been purely for the sake of clarity in the description. There may well be a set of contacts operated by the release plunger as shown in the drawings. These contacts may be used, for example, to control a "busy" or "clear" signal.

Although the switch mechanism of our present invention has been described as relating to an interoffice communication system, it should be understood that the relationship was used for the purpose of illustration and was not intended to limit the use of the mechanism to such systems.

What is claimed is:

1. An electric circuit switching mechanism comprising a plurality of depressible contact operating plungers, means for locking said plungers in their depressed position, said means including a first latch plate and a second latch plate, said latch plates lying in a common plane and having complementary apertures, said apertures being normally biased into misalignment, cam means associated with each of said plungers for aligning at least one of said apertures in one of said latch plates with the complementary aperture in the other of said latch plates when one of said plungers is depressed, said latch plates being cooperatively engaged with said cam means to lock said plungers in their depressed position, and a release plunger having a cam means associated therewith which, upon operation of said release plunger, effects an alignment of all of said apertures whereby any contact operating plunger previously locked in its depressed position is released.

2. An electric circuit switching mechanism comprising a plurality of depressible contact operating plungers, means for locking said plungers in their depressed position, said means including a first latch means common to all of said plungers, a second latch means comprising an independent latch segment for each of said plungers, said first and second latch means being disposed in a common plane and having complementary apertures, said apertures being normally biased into misalignment, cam means associated with each of said plungers for aligning at least one of said apertures in one of said latch plates with the complementary aperture in the other of said latch plates when one of said plungers is depressed, said latch means being cooperatively engageable with said cam means to lock said plungers in their depressed position, and a release plunger having a cam means associated therewith which, upon operation of said release plunger, effects an alignment of all of said apertures whereby any contact operating plunger previously locked in its depressed position is released.

3. An electric circuit switching mechanism comprising a plurality of depressible contact operating plungers, a channel member having an opening for each of said plungers, a first latch member lying in one half of said channel and common to all of said plungers, a second latch member lying in the other half of said channel adjacent to said first latch member, said latch

members having complementary apertures normally biased into misalignment, cam means secured to each of said plungers, said cam means being adapted upon the depressing of one of said plungers to align at least one of said apertures in one of said latch plates with the complementary aperture in the other of said latch plates, said first and second latch means being cooperatively engageable with said cam means for locking said plungers in a depressed position, and a release plunger having a cam means thereon which, upon operation of said release plunger, effects an alignment of all of said apertures whereby any operating plunger previously locked in its depressed position is released.

4. An electric circuit switching mechanism comprising a plurality of depressible contact operating plungers, a channel member having an opening for each of said plungers, a first latch member lying in one half of said channel and common to all of said plungers, a second latch member lying in the other half of said channel adjacent to said first latch member and being common to all of said plungers, said latch members having complementary apertures normally biased into misalignment, and cam means on each of said plungers, said cam means being adapted, upon the depressing of one of said plungers, to align said apertures, said first and second latch means being cooperatively engageable with said cam means for locking said plungers in a depressed position, the depressing of any one of said plungers effecting the release of any other plunger previously locked in a depressed position.

5. An electric circuit switching mechanism comprising a plurality of depressible contact operating plungers, a framework for supporting said plungers, means for locking said plungers in depressed position, said means including a first and a second latch plate common to all of said plungers, said latch plates lying in a common plane and having a plurality of complementary apertures each adapted to receive one of said plungers, said latch plates being normally biased in opposite directions to misalign said complementary apertures, and cam means secured to each of said plungers, said latch plates being slidably mounted in said framework whereby said plates may be moved to a position of alignment of said apertures under the influence of one of said cams when one of said plungers is depressed to permit the passage of said cam through said aperture, said latch plates being cooperatively engageable with said cams to lock said plunger in a depressed position.

6. The invention as set forth in claim 5 and characterized by the addition of a release plunger having a cam secured thereto which, upon operation of said release plunger, effects an alignment of all of said apertures releasing any contact operating plunger previously locked in a depressed position.

7. The invention as set forth in claim 5 and characterized by the addition of means operable from a remote position to release any of said plungers locked in a depressed position.

8. The invention as set forth in claim 7 wherein said means includes an electro-mechanical device having an armature, said armature being mechanically coupled to said latch plates whereby, upon excitation of said device, said latch plates are moved to a position of alignment of said apertures, releasing any plunger previously depressed.

9. An electric circuit switching mechanism comprising a plurality of depressible contact operating plungers, a framework for supporting said

plungers, means for cumulatively locking said plungers in an operating position, said means including a first latch member mounted in said framework common to all of said plungers, a second latch member comprising an independent latch segment for each of the plungers, said first and second latch members being disposed in a common plane and having complementary apertures adapted to receive each of said plungers, said latch members being normally biased in opposite directions to misalign said complementary apertures, cam means secured to each of said plungers, said latch members being slidably mounted in said framework whereby the aperture of one of said segments and the aperture of said first latch member may be moved to a position of alignment under the influence of one of said cams when one of said plungers is depressed to permit the passage of said one of said

cams through said aperture, said latch members being cooperatively engageable with said cam to lock said plunger in a depressed position, and a release plunger having a cam means secured thereto which, upon operation of said release plunger, effects an alignment of all of said apertures whereby any operating plunger previously locked in its depressed position is released.
